W. D. WARNER.
AEROPLANE CONTROL.
APPLICATION FILED OCT. 4, 1917.

1,283,607.

Patented Nov. 5, 1918.

UNITED STATES PATENT OFFICE.

WILLIAM DESHLER WARNER, OF DAYTON, OHIO.

AEROPLANE CONTROL.

1,283,607.

Specification of Letters Patent.

Patented Nov. 5, 1918.

Application filed October 4, 1917. Serial No. 194,660.

To all whom it may concern:

Be it known that I, WILLIAM DESHLER WARNER, citizen of the United States, residing at Dayton, in the county of Montgomery and State of Ohio, have invented certain new and useful Improvements in Aeroplane Controls, of which the following is a specification.

My invention relates to aeroplanes or flying machines and more particularly to the control means therefor. While the construction and device forming the subject matter hereof is particularly designed for use upon aeroplanes of the stick controlled type, it is to be understood that it is not necessarily limited to this particular type of machine but may be applied to other types of flying machines or other vehicles, or to the control lever of apparatus or machines of different character such as machine tools or other apparatus under conditions wherein it is desirable that the hands of the operator be free for various manipulative actions without releasing control of the apparatus.

The object of the invention is to simplify the structure, as well as the means and mode of operation of such control apparatus whereby it will not only be cheapened in construction, but will be efficient in operation, universal in its application, easily and quickly applied, readily adjusted to suit the convenience of the operator, and unlikely to get out of repair.

A further object of the invention is to provide a simple means by which governing control may be maintained over the control element of an aeroplane or other vehicle or apparatus, independent of manual or pedal effort, thus enabling the operator to employ his hands and his feet for different operations.

With the above primary and other incidental objects in view as will more fully appear in the specification, the invention consists of the features of construction, the parts and combinations thereof, and the mode of operation, or their equivalents, as herein-after described and set forth in the claims.

Referring to the drawings, Figure 1 is a sectional view of a portion of an aeroplane fuselage disclosing the "stick" control lever to which the present invention has been applied. Fig. 2 is a perspective view illustrating the mode of using the invention. Fig. 3 is a detail perspective view of the control lever attachment detached therefrom. Fig.

4 is a top plan view thereof. Fig. 5 is a detail sectional view through the bearing sleeve or hub. Fig. 6 illustrates the device applied to a wheel control mechanism.

Like parts are indicated by similar characters of reference throughout the several views.

In the drawings, 1 is the body portion or fuselage of the aeroplane which contains the cock pit 2 within which the operator is stationed. Located within the cock pit 2 is a chair or seat 3 in front of which is the control lever 4. As commonly constructed the control lever 4 is mounted for oscillatory movement in different planes. The usual method of stick control is to arrange and connect the lever 4 in such manner that its fore and aft oscillation controls the elevator to vary the vertical inclination of the machine. At the same time the lever 4 by its lateral or transverse oscillation serves to control the ailerons or the warping of the wings as the case may be, in order to maintain the equilibrium of the machine and assist in banking on turns or deviations from a straight course. As shown in the drawing, the control lever 4 is pivotally connected at 5 to a rock shaft 6 mounted in suitable bearings 7 and to the lever 4 is connected a link 8 or pitman 8. The pitman 8 by its longitudinal movement upon the fore and aft oscillation of the lever 4 controls the elevator, while the rocking of the shaft 6 upon the transverse oscillation of the lever regulates the ailerons or serves to warp the wings or planes.

The construction thus far described, forms no part of the invention *per se* but is a common aeroplane control construction which is here described only in order that the application and use of the device forming the subject matter of the present invention may be more readily and thoroughly understood.

It may be further said that in the same general construction the rudder is operated to effect lateral guidance by foot or pedal controlled means such as the foot bar 9, Fig. 2.

In order that the stick control lever 4 may be held fixedly in any adjusted position or may be shifted fore or aft or transversely as circumstances may necessitate, while the operator employs his hand in the manipulation of a machine gun, a photographic camera, signaling apparatus, or hand fire arms, or in map making, taking observa-

tions, or in the adjustment of his engine or apparatus, is the primary object of the present invention. To this end there is provided upon the control lever 4 a pair of oppositely disposed concave leg engaging pallets 10 interconnected one with the other by an intermediate yoke 11 embodying therein a hub or sleeve 12 through which the shaft of the control lever 4 extends. The interconnected pallets 10 are adapted to be engaged upon the lever 4 in any position of vertical or rotary adjustment by means of a set screw 13 which may engage the shaft of the lever 4 directly but preferably engages a clamping or bearing plate 14 adjustably seated in the inner periphery of the sleeve or hub 12. The set screw 13 by which the clamping action of the bearing plate 14 is effected, is preferably positioned at an inclination to the axis 15 of the lever 4, being normally positioned rearwardly and upwardly for easy and ready access. The outer faces of the pallets 10 are preferably although not necessarily concaved to agree with the anatomical contour 20 of the operator's limbs, at a point adjacent to the inner side of the knee. To prevent any undue chafing or rubbing, the rear edge of the pallet is preferably formed into an inward turned lip 15. In order to afford a sufficiently tenacious engagement of the operator's legs with the control device the concave or outer faces of the pallets 10 are 25 preferably roughened or corrugated. In the drawing such corrugations or roughened surface has been shown in the form of vertically disposed ribs or beads arranged in substantially parallel relation.

In operation, the interconnected leg engaging pallets 10 are adjusted vertically upon the control lever 4 to a position in which they will be conveniently and comfortably engaged or gripped between the operator's limbs immediately above the knees as shown in Fig. 2, while the operator's feet are engaged with the foot bar or pedal steering device 9. In the position shown in Fig. 2, the control lever 4 may be firmly and fixedly held in any adjusted position by the gripping action of the operator's legs, leaving his hands free for such purposes as may be necessary, while his feet control the steering apparatus. At the same time, without the necessity of manual or pedal operation, by a lateral or swinging knee action the control lever 4 may be shifted transversely as circumstances may necessitate to maintain the even balance or equilibrium of the machine. In the control of large machines or under such atmospheric or wind conditions under which the ailerons afford considerable resistance, or the planes resist their warping action the present device will be found of material and valuable assistance in supplementing the manual manipulation of the lever. In addition to the lateral adjustment of

the lever 4 by the knee action, the operator may by a bodily shifting movement either with or without movement of the seat 3 effect a fore and aft adjustment of the lever 4 while held between the knees, independent 70 of manual effort.

This device is now being used with material and marked beneficial results at the Government Aviation Training School at Dayton, Ohio, where its practicability and 75 utility have been thoroughly demonstrated.

Fig. 6 illustrates the device applied to a wheel control mechanism. In this form of control the wheel 16 is mounted upon an oscillatory yoke 17. Pivoted concentric with 80 the wheel 16 is a pendant arm 18 capable of free swinging movement independent of the wheel 16. A clamp 19 is provided for interengaging the arm 18 at will with the wheel. Mounted upon the arm 18 are the 85 pallets 10 as before described. The operator is enabled to oscillate the wheel by a lateral shifting knee movement and by a fore and aft movement can swing the yoke 17. The adjustment of the device and its 90 mode of use are as before described.

From the above description it will be apparent that there is thus provided a device of the character described, possessing the particular features of advantage before enumerated as desirable but which obviously is susceptible of modification in its form, proportion, detail construction or arrangement of parts, without departing from the principle involved or sacrificing any of its ad- 95 vantages.

While in order to comply with the statutes, the invention has been described in language more or less specific as to certain structural features, it is to be understood 105 that the invention is not limited to any specific details, but that the means and construction herein described comprise but one mode of putting the invention into effect, and the invention is therefore claimed 110 broadly in any of its possible forms or modifications within the scope of the appended claims.

Having thus described my invention, I 115 claim:—

1. The combination with an aeroplane embodying an oscillatory control lever capable of both lateral and fore and aft movement, of a pair of oppositely disposed leg engaging pallets carried by the control lever 120 adapted to be gripped between the legs of the operator.

2. The combination with a movable control member, of a pair of oppositely disposed leg engaging pallets connected therewith and adapted to be gripped between the legs of the operator whereby the control member is held and manipulated by knee action of the operator independent of manual or pedal effort.

3. The combination with a movable control element, of a pair of oppositely disposed leg engaging pallets adjustably mounted thereon and adapted to be gripped between the legs of the operator thereby enabling the governing of the control member in its different directions of movement by knee action of the operator.
4. The combination with a movable control member, of a pair of oppositely disposed pallets located on opposite sides of the control member, an intermediate yoke connecting said pallets, said intermediate yoke being adjustably connected with the control member.
5. The combination with a movable control member, of a pair of oppositely disposed pallets, an intermediate yoke integrally connecting said pallets, said yoke having therein an eye through which the control member extends.
6. A control member attachment of the character described, comprising a pair of oppositely disposed concave pallets on opposite sides of the control member, and an intermediate yoke integral with the pallets connecting the pallets one with the other.
7. A control member attachment of the character described, comprising a pair of oppositely disposed interconnected concave pallets, said pallets having a series of vertical corrugations in their concave faces.
8. A control member attachment of the character described, comprising a pair of oppositely disposed interconnected concave pallets, the concave faces of said pallets being provided with frictional engaging surfaces.
9. The combination with an aeroplane including a laterally movable oscillatory control lever, of a pair of oppositely disposed leg engaging pallets carried thereby and adapted to be engaged between the legs of the operator, whereby said lever may be shifted laterally by a lateral knee movement of the operator independent of manual or pedal effort.
10. The combination with an aeroplane including an oscillatory lever movable in a fore and aft direction, of a pair of oppositely disposed leg engaging pallets carried thereby and adapted to be engaged between the legs of the operator, whereby said lever may be shifted fore and aft by a shifting movement of the operator's body independent of manual or pedal effort.

In testimony whereof, I have hereunto set my hand this 25th day of September A. D. 1917.

WM. DESHLER WARNER.
